UNITED STATES PATENT OFFICE.

ABIJAH BENJAMIN BENNETT, OF OPELIKA, ALABAMA.

COMBINED CIGAR-CUTTER AND MATCH-SAFE.

No. 890,119.

Specification of Letters Patent.

Patented June 9, 1908.

Application filed April 30, 1906. Serial No. 314,582.

To all whom it may concern:

Be it known that I, ABIJAH BENJAMIN BENNETT, a citizen of the United States, residing at Opelika, in the county of Lee and State of Alabama, have invented certain new and useful Improvements in a Combined Cigar-Cutter and Match-Safe, of which the following is a specification.

This invention relates to an improvement in combined cigar cutters and match safes, and more particularly to that type of device wherein the actuation of the cigar cutter serves to automatically eject a match from the match safe and position the same for ignition.

The object of the present invention is the provision in a device of this character of improved means actuated through the actuation of the cigar cutter for ejecting a single match from the match safe and delivering the same into position so as to be ignited when withdrawn by the user.

A further object of the invention is the provision of improved means for effecting the ignition of the match.

Other objects of the invention will be apparent from the detailed description herein-after, when read in connection with the accompanying drawings forming a part hereof, wherein a preferable embodiment of my invention is shown and wherein like numerals of reference refer to similar parts in the several views.

In the drawings:—Figure 1 is a perspective view of my improved device. Fig. 2 is a longitudinal section. Fig. 3 is a section on line 3—3 of Fig. 2, and Fig. 4 is a front elevation with parts broken away.

Referring now more particularly to the drawings A designates a box-like casing in the upper portion of which is the match receptacle A' having the inclined bottom a and in the lower part of which is positioned a drawer A² adapted to receive the severed ends of the cigars, access being had to said drawer by a door A³ in the back of the casing. The front wall of the casing is provided with an elongated aperture a' therein, through which the ends of the cigars are designed to be introduced. Secured to the exterior of the front wall of the casing adjacent the opening a' therein is a fixed plate B having in one side thereof an inwardly extending recessed portion b provided with a beveled edge. Positioned at one side of the fixed

plate B is a laterally movable plate B', which is normally held in yieldable engagement with the adjacent edge of the fixed plate B by means of a suitable spring b'. The plate B' is provided with an inwardly extending recess b² in one edge thereof, which is similar in form to the recess b in the fixed plate B and is designed to coöperate therewith to form a substantially circular opening through which the tip of the cigar is introduced. From this construction, it will be apparent that various sized cigars may be inserted through the aperture a' in the casing and that the cigar will be firmly held by the plates B and B' during the severance of its tip by the cutter, to be hereinafter described.

C designates the cutter, which is in the form of a plate which is pivotally secured to the inner side of the front wall of the casing and is movable across the aperture a' therein.

D designates an actuating lever which is fulcrumed in any suitable manner in one of the side walls of the casing and the forward end of which projects within the casing and is positioned slightly in rear of the front wall thereof. The outer end of the lever D is connected with the free end of the cutter C by means of a downwardly extending link d.

E designates a plate, which is secured to the inner side of that portion of the front wall of the casing, which forms a part of the match safe, the lower end of the bottom of said match safe terminating short of said plate so as to leave a slight space therebetween.

F designates a vertically movable ejector plate which is designed to occupy the space between the bottom of the match safe and the plate E. The ejector plate F is provided with a plurality of pins f projecting from the side thereof, which are designed to engage grooves f' formed in the side walls of the casing. The front wall of the casing terminates short of the top thereof and the grooves f' in the sides of the casing extend upwardly beyond the top of the front wall and are curved forwardly, for a purpose which will be herein-after more particularly set forth. The upper portion of the ejector plate F is made flexible so that it may conform to the configuration of the groove f' during its upward travel. The upper edge of the ejector plate is slightly dished so as to form a seat for a single match. A link d² connects the extreme outer end of the actuating lever D with the ejector plate.

Secured to the upper portion of the front

wall of the casing A is a box or tray G, which is designed to receive a match after the same has been thrown over the front wall of the casing by the ejector plate F, a portion of the 5 front and side walls of said box being cut away to afford the withdrawal of the match by the user, as will be hereinafter set forth. H designates a striking plate having a roughened upper surface, which is designed to 10 occupy one end of the box or tray G. The plate H is provided at its forward edge with a plurality of pins or projections h, which are designed to loosely engage apertures formed in the front wall of the casing A and the plate 15 is yieldably supported by a leaf spring I which is secured to the bottom of the box or tray G and bears against the under side thereof. The plate H is introduced into the box or casing G through a slot g' formed in the 20 front wall thereof and accidental displacement thereof is prevented by a screw g², which is adjustably secured in the bottom of the box or casing G and extends upwardly into proximity to the under side of the striking plate H. From this construction it will be apparent when the screw g² is properly adjusted the striking plate H cannot be depressed a sufficient amount to permit its withdrawal through the slot g', but that if it 25 is desired to replace the plate for any reason the screw g² can be lowered and the plate readily withdrawn. K designates a supplemental striking plate, which is supported in the box or tray G directly above the striking 30 plate H, the forward end of said striking plate K being upturned slightly to permit the head of the match to be readily drawn between the two plates. The striking plate K is provided with an upwardly extending portion k, which has a pin and slot connection 35 with the front wall of the box or tray G to permit the vertical movement of said striking plate. The striking plate K is normally held in yieldable engagement with the striking 40 plate H by means of a coil spring k', the lower end of which bears on the upper side of said striking plate and the upper end of which is secured to a suitable cross bar k² in the box or tray G. L designates a block, 45 which is supported upon the bottom of the box or tray G and is preferably inclined downwardly towards the front thereof. To prevent the matches in the match receptacle from crowding in the lower end 50 thereof, I provide a partition therein, which extends into proximity to the bottom thereof. Access to the match safe is obtained by a 55 suitable lid in the top of the casing, which also covers the box or tray G.

The weight of the cutter C, the ejector plate F, and the links connecting them to the 60 end of the lever D is such that the handle of said lever will normally be maintained by 65 gravity in its raised position, the upward

movement of said handle being limited by the contact of the lower end of the lever with the side wall of the casing.

From the above construction, it will be apparent that if the tip of a cigar be inserted in the aperture a' of the casing and the handle of the lever D depressed, the cigar tip will be severed and simultaneously the ejector plate will lift a match and throw the same over the top of the front wall of the casing. The 70 match will fall to the bottom of the box or tray G, the head thereof falling on the striking plate H and the opposite end thereof on the block L. If now the user grasps the end of the match and draws the same through the 75 cut-away portion of the box or tray G, the head thereof will be drawn between the striking plates H and K and ignited.

I do not desire to limit myself to the precise form and construction shown in the 80 drawings, as it is obvious that many minor changes may be made thereto without departing from the spirit of the invention.

I claim:

1. A match safe provided with a flexible 90 ejector plate and ways for deflecting the movement of the upper portion of said plate.

2. In a single delivery match safe, a vertically movable flexible ejector plate and ways for deflecting the movement of the upper 95 portion of said plate.

3. In a match safe having a discharge opening in the front wall thereof, a vertically movable flexible ejector plate positioned in rear of the front wall, and means for causing 100 the deflection of the upper portion of said deflector plate at the end of its upward travel.

4. The combination in a match safe having a discharge opening in the front wall thereof, of guideways in the side walls extending upwardly and forwardly into proximity to the 105 discharge opening, and a flexible ejector plate slidably secured in said guideways.

5. In a combined cigar cutter and match safe, a flexible ejector plate for effecting the 110 delivery of matches from the safe, means for deflecting the movement of the upper portion of said plate a pivoted cutter, and a single lever for actuating said ejector plate and cutter.

6. In a combined cigar cutter and match safe, a flexible ejector plate for effecting the 115 delivery of the matches, means for deflecting the movement of the upper portion of said plate a pivoted cutter, a pivoted lever, and links connecting said lever with said ejector plate and cutter.

7. In a combined cigar cutter and match safe, a flexible ejector plate for effecting the 120 delivery of the matches, means for deflecting the movement of the upper portion of said plate a pivoted cutter, a pivoted lever, and links connecting the outer end of said lever with the ejector plate and the free end of the cutter, whereby the weight of said parts will 125 130

serve to normally maintain the handle of said lever in a raised position.

8. In combination with a match safe and means for ejecting a match therefrom, a box positioned to receive the ejected match and having a cut-away portion to permit its removal therefrom, a striking plate in one end of said box adapted to coöperate with the head of the match to effect the ignition thereof, and a block in the opposite end of the box adjacent the cut-away portion thereof adapted to support the opposite end of the match.

9. In combination with a match safe and means for ejecting a match therefrom, a box positioned to receive the ejected match and having a cut-away portion to permit its removal therefrom, and means for effecting the ignition of the match when withdrawn therefrom, said means including a striking plate removably secured in said box, and means for normally preventing the removal of the striking plate from the box.

10. In a match safe, a match compartment having a discharge opening communicating therewith, an ejector plate adapted to be moved upwardly through said match compartment, the upper portion of said ejector plate being flexible and provided with a seat

therein for a match, and means for deflecting the flexible portion of the ejector plate when the same is moved opposite the discharge opening.

11. In a combined match safe and cigar cutter, a flexible ejector plate for effecting the delivery of the matches from the safe, means for deflecting the movement of the upper portion of said plate, said means including ways in the safe and pins carried by the plate and engaging said ways, a pivoted cutter, and a single lever for actuating said ejector plate and cutter.

12. In a combined match safe and cigar cutter, a flexible ejector plate for effecting the delivery of the matches, means for deflecting the movement of the upper portion of said plate, said means including ways in the safe and pins carried by the plate and engaging said ways, a pivoted lever, and links connecting said lever with said ejector plate and cutter.

In testimony whereof I have signed my name to this specification in the presence of two subscribing witnesses.

ABIJAH BENJAMIN BENNETT.
